UNITED STATES PATENT OFFICE.

CLINTON D. PALMER, OF CHICAGO, ILLINOIS, ASSIGNOR TO SEARS, ROEBUCK AND CO., OF CHICAGO, ILLINOIS, A CORPORATION OF ILLINOIS.

PER-POSITIONING DEVICE FOR TYPE-WRITERS.

1,108,612.

Specification of Letters Patent.

Patented Aug. 25, 1914.

Application filed January 30, 1913. Serial No. 745,123.

To all whom it may concern:

Be it known that I, CLINTON D. PALMER, a citizen of the United States, residing at Chicago, in the county of Cook and State 5 of Illinois, have invented certain new and useful Improvements in Paper-Positioning Devices for Type-Writers, of which the following is a specification.

This invention relates to typewriting machines and contemplates an improved means for uniformly positioning the paper on the platen.

The embodiment of the invention shown in the drawings is intended more particularly for typewriting on cards, such, for example, as are used in card indexes and other card systems. It should be understood, however, that the invention is not limited to such use. In typewriting on cards, it is often desirable that the first line of writing should be spaced at a uniform distance from the tops of the cards, this being particularly true when the cards are ruled, or when they are printed and have 25 blank spaces left to be filled in on the typewriter.

One of the objects of this invention is to provide improved means for stopping the paper, so that the forward edge thereof shall 30 occupy a definite or uniform position with reference to the writing line.

Another object is to provide a stopping means the use of which shall require no attention on the part of the operator.

35 A further object is to provide paper-positioning means which may be manufactured separately as an attachment and may be conveniently applied to existing machines.

The purposes and advantages of the invention will be further understood from the following detailed description.

In the accompanying drawings, Figure 1 is a fragmental front elevation of a typewriting machine embodying my improvements. Fig. 2 is a fragmental front elevation of the stop means showing the parts in a different position from Fig. 1. Fig. 3 is a transverse vertical sectional view taken on the line 3-3 of Fig. 1. Fig. 4 is 45 a fragmentary sectional view similar to Fig. 3, but showing the parts in a different position. Fig. 5 is a vertical sectional view of the well-known Monarch machine, showing my invention applied thereto.

In the present instance, I have illustrated my invention as embodied in an attachment which is built separate from the machine and is arranged to be applied to any of the standard visible typewriters. It will be 60 understood, however, that my improvements may be built as a permanent part of the typewriter, if desired.

The means for guiding the cards into uniform position on the platen comprises a member 5 having two like passage-ways or chutes 6 and 7 therein, the rear passage-way being of a length to receive the card when inserted sidewise into the machine, and the forward passage-way being adapted to receive the card when inserted endwise. The end walls of the passage-ways are preferably flared or tapered at their receiving ends, as clearly shown in Fig. 1. The passage-ways also are preferably tapered from top to bottom, as shown in Fig. 3. If desired, a portion of the rear wall of the member may be cut away, as at 8 to facilitate grasping a card inserted into either of the passage-ways. When my invention is embodied in the form of an attachment, the member 5 is mounted upon the paper shelf 9 of the typewriter. The member 5 may be secured to the paper shelf by means such as screws 10 passing through the ends of the member into said shelf and having nuts threaded on their rear ends. As the card leaves the lower end of the guide member 5, it passes between the platen 11 and the curved guide plate 12, being held against the platen by spring-pressed rollers 13 and 14 in the usual way.

In order to stop the advancing edge of the card at a uniform distance from the writing line on the platen, I provide the following means. A bracket 15 is secured to the frame 16 of the typewriter in any suitable way, as by means of screws or bolts 17 passing through said bracket and into the U-shape portion of the typewriter frame which lies just beneath the platen. The bracket 15 comprises a base or attaching portion 18 from one end of which a finger 19 rises, the upper end of said finger lying in front of the platen 11 and serving to guide the card and hold it close to the platen. The bracket 15 extends upwardly from the other end of the attaching portion 18 and has a relatively wide upper end 20. A stop plate 21 has journals 22 pivoted in out-

wardly extending ears 23 on the end portion 20. The upper edge of said stop plate has a rearwardly extending flange or lip 24 arranged to be moved toward the platen and to be engaged by the advancing edge of the card.

From an inspection of Fig. 1, it will be noted that the finger 19 and the portion 20 lie at opposite sides of the ribbon-vibrating device 25 and behind the ribbon 26, so that the feeding and vibrating of the ribbon is not interfered with. Said parts 19 and 20 act to hold the card close to the platen at opposite sides of the striking point of the type.

A lever 27 is pivoted between its ends at 28 on the finger 19, one end of said lever having an angular arm 29 extending upwardly toward the stop-plate 21. Preferably, the arm 29 has a slot 30 therein through which a guide screw 31 extends, said screw being threaded in the bracket 15. The upper end of the arm 27 is beveled as at 32, and is arranged to engage a downwardly extending lug 33 on the stop plate 21. The lower end of said lug is beveled or bent outwardly, so that when the arm 29 is raised the beveled end thereof will move the lug outwardly and force the lip 24 on the stop plate into the path of a card. A leaf spring 34, fixed to the bracket portion 20, engages the stop plate 21 and tends to hold the lip 24 out of the path of the card. A coiled spring 35, secured at one end to the lever 27 and at its other end to the base 18 of the bracket, tends to pull the arm 29 downwardly.

The opposite end of the lever 27 has a cam portion 36 thereon comprising two inclined sides and a top or rest portion. A downwardly extending arm 37 is fixed on one end of the carriage frame 38, the lower end of said arm being arranged to ride up on the incline of the cam 36 as the carriage is moved to starting position, and to rest on the top of the cam when the carriage is in its initial position, so that the arm 29 on the lever 27 will be forced upwardly to hold the stop flange or lip 24 in position to stop the card as it is fed by the rotating platen.

The length of the cam arm 27^a of the lever 27 is preferably made such that the top of the cam will be in line with the adjacent end wall of the longer passage-way in the guide member 5. The carriage-stop device (the marginal stop) on the typewriter will be so positioned that the arm 37 will bear on the top of the cam 36 when the carriage is in its initial or starting position.

Fig. 5 illustrates the mechanism of the Monarch typewriter substantially as shown in Patent No. 972,578, dated Oct. 11, 1910. As explained in said patent, 41 is a universal bar that underlies the key levers 8^a. Said bar is secured to arms 42 which are

pivoted at 43, the parts 41, 42 and 43 forming a universal frame from which an arm 46 projects rearwardly. An upwardly extending link 47 connects the arms 46 to the forwardly extending arm of a dog-rocker 50 pivoted at 51. The dog-rocker carries the feed dogs 6^a. Each key lever has a sub-lever 11^a pivoted thereto at 12^a. Each sub-lever is pivoted to the framework at 20^a. The upper end of each sub-lever is pivoted at 13^a to a draw-link 14^a which is connected to one of the type bars 16^a.

In use, a card is dropped into one of the passage-ways in the guide member 5 and the platen 11 given a rapid whirl, the operator 80 paying no attention to the extent of the rotation. As soon as the advancing edge of the card strikes the rearwardly-projecting stop lip 24, further advance of the card will be checked, the pressure of the paper-feed 85 rolls 13 and 14 being so adjusted that when the advancing edge of the card strikes the lip 24, the platen slips on the card until the platen comes to rest. As the first character is written on the card, the escapement mechanism of the typewriter permits the carriage to travel to the left in the usual way, so that the arm 37 will move off the cam 36, thereby permitting the spring 35 to draw the opposite end of the lever 27 downwardly and release the stop plate 21 which then moves into inoperative position. Thus as soon as the first character has been written, the card 95 may, if desired, be freely fed upwardly by rotating the platen through the line space 100 mechanism in the usual way. A depression of the space bar likewise throws out the line-stop 24.

When matter is to be written on the card along the other dimension thereof, the card 105 is dropped into the other passageway in the guide-member 5, and the platen given a spin to carry the card to writing position.

The two passageways 6 and 7 are so arranged relatively to each other that one 110 serves as a marginal stop for one margin of a card, while the other passageway serves as a marginal stop for another margin of the same card.

It will be seen that my invention provides 115 means for positioning a card with respect to its margins, and in definite relation to the writing line, without requiring any attention on the part of the operator other than to drop the card into the guide and give the 120 platen a spin. Thus much time may be saved in the production of card records and the like.

While I have herein described my invention in considerable detail, I realize that 125 many changes may be made by those skilled in the art, without departing from the scope of the appended claims, and I therefore do not limit any invention to the exact construction herein disclosed.

I claim as my invention:

1. In a typewriter, a framework, a platen carriage mounted on the framework, feed mechanism on the carriage, two card-holding fingers mounted on the framework adjacent to the printing point, one of said fingers being fixed in position, and a card-stopping member mounted on the upper portion of said fixed finger for engaging the upper edge 5 of a card fed by said feed mechanism.
2. In a typewriter, a framework; a paper carriage movable from right to left and vice versa on the framework; a paper stop mechanism on the framework, said stop mechanism tending to assume an inoperative position; and means attached to the carriage for actuating said mechanism.
3. A typewriting machine comprising a frame-work, a carriage movably mounted thereon and having a platen, guide means to direct cards into uniform position on said platen, a movable stop device on the framework, means for moving said stop device into position to stop a card, and means mounted on said carriage for operating said moving means.
4. In a typewriter, a framework, a carriage movable from right to left and vice versa on the framework; a platen on the carriage; type bars arranged to strike the platen; key levers for actuating said type bars; an escapement for controlling the movement of the carriage, said escapement being operated by the key levers; a paper stop on the framework; a member on the framework for actuating the stop; and a member on the carriage arranged to engage said other member in a certain position of the carriage.
5. A typewriter comprising a frame-work, a carriage mounted thereon and having a platen, means mounted on said frame-work for stopping a card at a definite position with relation to the writing line, and means on the carriage for operating said stopping means.
6. A typewriter having a framework, a carriage mounted to move on the framework, a movable stop device on the framework arranged to be engaged by the forward edge of the advancing sheet of paper, and means on the carriage for moving said stop device into operative position.
7. A typewriter comprising a stationary portion, a carriage mounted thereon and having a platen, a paper stop member mounted on said stationary portion for movement toward and away from said platen, means tending to hold said stop member in inoperative position, a lever mounted on said stationary portion and arranged to move said stop member into operative position, and means on said carriage for swinging said lever.
8. A typewriting machine comprising a frame-work, a carriage mounted thereon and having a platen, a bracket mounted on the frame-work beneath the carriage and extending upwardly in front of the carriage, a stop member pivoted on said bracket and arranged to be engaged by the forward edge of the paper, a lever pivoted between its ends on said bracket, one end of said lever being arranged to swing said stop member toward the platen, and means mounted on the carriage for engaging the other end of said lever to swing it.
9. An attachment for typewriting machines consisting of an attaching portion; two card-holding fingers rigid with the attaching portion; a card-stopping member pivotally mounted near the upper end of one of said fingers, said attachment also comprising a pivoted lever arranged to move said card-stopping member in one direction; and a spring for moving said card-stopping member in the opposite direction.
10. A typewriter comprising a framework; a carriage mounted for movement from right to left and vice versa on said framework; a paper-stop member; a support fixed to the framework for movably supporting said paper-stop member; a lever mounted on said support for operating said paper-stop member; and a part mounted at the left hand end of the carriage for actuating said lever.
11. A typewriter comprising a framework; a carriage mounted for movement on the framework; paper-stop means mounted on the framework, said stop-means being normally in inoperative position, said stop-means including an actuating lever; and a part mounted on the carriage and arranged to engage and move said lever in the travel of the carriage to move the stop-means into operative position.
12. A typewriter comprising a framework, a carriage mounted thereon, paper stop mechanism mounted on said framework and including a lever having a cam portion, and a part mounted on the carriage arranged to engage said cam portion and thus operate said paper stop mechanism.
13. A typewriter comprising a framework, a carriage mounted thereon, paper stop means mounted on said frame-work and adapted to engage the advancing edge of the sheet for positioning the sheet, said stop means being normally in inoperative position, an actuating lever having a cam portion thereon, and a part mounted on said carriage adapted to engage said cam portion in the travel of the carriage for actuating said lever to move the stop means into operative position.
14. In a typewriter, a carriage, a platen on the carriage, and a paper stop releasable by the movement of the carriage.
15. A typewriter comprising a framework; a carriage movable from right to left and vice

4. A typewriter comprising a framework; paper-stop means mounted on the framework, said stop-means tending to assume an inoperative position; and means actuated by the right-hand travel of the carriage to move the stop-means into operative position.

16. A typewriter comprising a framework; a carriage mounted for movement from right to left and vice versa on the frame-

work; and paper-stop means automatically 10 movable into inoperative position by the travel of the carriage to the left.

In testimony whereof I affix my signature in the presence of two witnesses.

CLINTON D. PALMER.

Witnesses:

NICHOLAS A. WEIBAND,
FRANCIS E. ROBERTS.

It is hereby certified that in the grant and in the heading to the printed specification of Letters Patent No. 1,108,612, granted August 25, 1914, upon the application of Clinton D. Palmer, of Chicago, Illinois, for an improvement in "Paper-Positioning Devices for Type-Writers," the State of incorporation of the assignee was erroneously given as "Illinois" whereas said State should have been given as *New York*; and that the said Letters Patent should be read with this correction therein that the same may conform to the record of the case in the Patent Office.

Signed and sealed this 20th day of October, A. D., 1914.

[SEAL.]

J. T. NEWTON

Acting Commissioner of Patents
